UNITED STATES PATENT OFFICE.

HENRY C. WILLIAMS, OF YORK, PENNSYLVANIA.

COIN-CONTROLLED APPARATUS FOR RENTING UMBRELLAS.

1,347,831.

Specification of Letters Patent. Patented July 27, 1920.

Application filed April 11, 1919. Serial No. 289,349.

To all whom it may concern:

Be it known that I, HENRY C. WILLIAMS, a citizen of the United States, residing at York, in the county of York and State of Pennsylvania, have invented new and useful Improvements in Coin-Controlled Apparatus for Renting Umbrellas, of which the following is a specification.

The object of my invention is the provision of an apparatus constructed and arranged to securely hold an umbrella against unauthorized removal, and adapted to be controlled by the deposit of a coin or coins of predetermined denomination, and also adapted to be expeditiously and easily manipulated after the deposit of the coin or coins, so that the umbrella may be expeditiously and easily removed.

The invention also contemplates the provision of means whereby when the umbrella is returned to and secured in the apparatus and a coin constituting the rental fee, say a 25¢ piece, is deposited in the apparatus, the coin or coins deposited in the first instance will be released for delivery to the party returning the umbrella.

Other objects and practical advantages will be fully understood from the following description and claims when the same are taken in connection with the drawings accompanying and forming part of this specification, in which:

Figure 1 is an elevation view illustrating the apparatus constituting the best practical embodiment of my invention that I have as yet devised.

Fig. 2 is a top plan view of the apparatus.

Fig. 3 is an enlarged vertical section taken through the coin-receiving means of the apparatus.

Fig. 4 is a vertical section taken at right angles to Fig. 3.

Figs. 5 and 6 are detail views, hereinafter explicitly referred to.

Fig. 7 is an enlarged perspective of one of the umbrella release levers hereinafter referred to.

Similar numerals of reference designate corresponding parts in all of the views of the drawings.

Among other elements my novel apparatus comprises a casing 1 which may be of wood or metal, in the discretion of the manufacturer.

Extending downwardly from the casing 1

and fixed with respect thereto, is a stand 2 on the face of which are umbrella holding loops 3, arranged one above the other in spaced relation, as best shown in Fig. 1. At its lower end the stand 2 is provided with a socket 4, designed and adapted to receive the lower end of an umbrella, with a view to holding the same against lateral manipulation. Movable rectilinearly within certain limits in the upper portion of the stand 2 is a loop-shaped umbrella securer 5 that is adapted to securely retain the umbrella handle and which comprises part of the organized lock mechanism, hereinafter specifically described.

Disposed below the top of the casing is a deposit receptacle 6 for earnings, and also disposed below said top is a second receptacle 7, having at its lower end what I denominate as a refund coin cup 8.

In addition to the umbrella securer 5, the organized lock mechanism comprised in my improvement includes a spring-pressed bolt 9 adapted to prevent closing of the securer 5 without retraction of the bolt by the manipulation of a complementary key, a rod member 10 adapted to be engaged by one end of the securer 5, coin slot 11, a lever 13 connected with a rod 14 connected to and extending forwardly from the lever 13, a member 15 connected to and extending forwardly from the lever 13 and having a slot adapted to be registered with the slot 11, release levers 16 and 17, and a coin-returning lever 18 having arms which reach into chutes comprised in the receptacle 7, Figs. 1 and 4. Slots 19 and 20 are also provided for the reception of two 50¢ coins. The lever 13 is fulcrumed at an intermediate point of its length on a bracket 12, and a retractile spring is connected to the inner arm of said lever to draw said arm forwardly when the securer 5 is released from levers 16 and 17 and drawn forwardly.

After the securer 5 is drawn forwardly for the release of an umbrella handle, the bolt 9 enters the notch shown in the rod 14, so that the umbrella on the return thereof cannot be again secured in the apparatus until the bolt 9 is retracted by a key (not shown) which is taken from the apparatus by the umbrella renter when he removes the umbrella.

It will be apparent from the foregoing that I have provided an apparatus which

specifically considered is designed to rent umbrellas, and is calculated to assure the return of a rented umbrella, inasmuch as the original 50¢ coins deposited as collateral for 5 the umbrellas may be recovered by the umbrella renting individual when he restores and properly secures the umbrella in the apparatus and after he deposits a 25¢ coin in the slot 11. This will be better understood 10 when it is stated that the operation of the apparatus is as follows:

The prospective umbrella renter deposits two fifty cent coins in the slots 19 and 20, and said coins, by acting on the levers 16 15 and 17, release the securer 5 so that said securer may be drawn outwardly for the removal of the umbrella. On such outward movement of the securer, the bolt 9 enters the notch in the rod 14 so that an umbrella 20 cannot be replaced in the securer until the bolt 9 is retracted by the key as before described. Outward movement of the securer 5 will be attended by such movement of the member 15 that the said number 15 will bar 25 the slot 11 and prevent the deposit of a coin therein. The deposited fifty cent coins will be supported by the lower arms of the levers 18. When, however, the rented umbrella is 30 returned to its position in the securer 5, and the securer is forced rearwardly (after the retraction of the bolt 9 by the key mentioned) the slot in the member 15 is registered with the slot 11. A twenty-five cents piece, constituting the umbrella rental, is 35 then passed through the slot 11, and said slot in the member 15, whereupon said coin, by acting on the upper arm of the lever 18 will swing the lower arms of the lever outwardly, and thereby permit the fifty cents pieces to drop to the cup 8. The umbrella 40 will then be again locked in the apparatus, and the released fifty cents pieces will be offered for return to the renter, whose province is to remove them from the cup 8. The 45 deposited rental coin (twenty-five cents) will drop into the receptacle 6 where it will be retained until removed by an authorized person.

Notwithstanding the capacity of function 50 ascribed to my novel apparatus, it will be readily appreciated that the apparatus is simple, compact and inexpensive in construction, and is well adapted to withstand the usage to which such apparatus is ordinarily subjected.

As hereinbefore indicated, the construction herein illustrated and described constitutes the best practical embodiment of my invention that I have as yet devised. It is 60 to be understood that I do not restrict myself to the specific construction and relative arrangement of parts, inasmuch as the scope of my invention is defined by appended claims.

65 Having described my invention, what I

claim and desire to secure by Letters-Patent, is:

1. A coin-controlled umbrella renting apparatus comprising a casing having in its top slots for coins of different denominations, a loop-shaped umbrella securer movable rectilinearly forwardly and backwardly in the front wall of the casing and having a beveled projection on one of its side arms, a key-controlled spring-pressed bolt, a rod 75 movable rearwardly in the front wall of the casing by an umbrella in the securer and having a notch for the engagement of said bolt, a lever fulcrumed at an intermediate point of its length and having its inner arm 80 connected with said rod, a retractile spring to move said arm of said lever forwardly, a rod connected to said inner arm of the lever and extending forwardly therefrom and bearing against one end of the umbrella securer, a guard connected to the outer arm of said lever and arranged to close the slot for the coin of smaller denomination when an umbrella is out of the securer and to render said slot open when the umbrella is in 90 the securer, a receptacle in communication with and extending downwardly from the slot for the coin of larger denomination and a delivery cup, a lever arranged to engage the lateral beveled projection on the umbrella securer and also arranged in said receptacle to be engaged and actuated by a coin placed in the upper portion thereof, a receptacle arranged below the slot for the coin of smaller denomination, and a lever 95 arranged to normally extend into the first-named receptacle to support the coin therein and having a portion extending into the second-named receptacle whereby the lever will be engaged by the deposited coin of smaller 100 denomination and moved to release the coin of larger denomination in the first-named receptacle.

2. A coin-controlled umbrella renting apparatus comprising a casing having in its top slots for coins of different denominations, a loop-shaped umbrella securer movable rectilinearly forwardly and backwardly in the front wall of the casing and having a beveled projection on one of its side arms, a key-controlled spring-pressed bolt, a rod 110 movable rearwardly in the front wall of the casing by an umbrella in the securer and having a notch for the engagement of said bolt, a lever fulcrumed at an intermediate point of its length and having its inner arm connected with said rod, a retractile spring to move said arm of said lever forwardly, a rod connected to said inner arm of the lever and extending forwardly therefrom and bearing against one end of the umbrella securer, a guard connected to the outer arm of 115 said lever and arranged to close the slot for the coin of smaller denomination when an umbrella is out of the securer and to render 120

said slot open when the umbrella is in the securer, a receptacle in communication with and extending downwardly from the slot for the coin of larger denomination and a delivery cup, a receptacle arranged below the slot for the coin of smaller denomination, means actuatable by a coin placed in the first-named receptacle to release the umbrella securer, and movable means extend-

ing into the first-named receptacle to temporarily support a coin in the upper portion thereof and also extending into the second-named receptacle to be engaged and actuated by a coin deposited therein for the release of the coin in the first-named receptacle. 10 15

In testimony whereof I affix my signature.
HENRY C. WILLIAMS.
